John C. Telfer, INVENTOR,
By *John C. Telfer*, ATTORNEY.

UNITED STATES PATENT OFFICE.

JOHN C. TELFER, OF PALATKA, FLORIDA.

DISK STEAM-ENGINE.

SPECIFICATION forming part of Letters Patent No. 359,906, dated March 22, 1837.

Application filed May 19, 1886. Serial No. 202,651. (No model.)

To all whom it may concern:

Be it known that I, JOHN C. TELFER, a citizen of the United States, residing at Palatka, in the county of Putnam, State of Florida, have 5 invented a new and useful Improvement in Disk Steam-Engines, which improvement is fully set forth in the following specification and accompanying drawings, in which—

Figure 1 represents a central section of a 10 disk-engine embodying my invention. Fig. 2 represents a section thereof at a right angle to Fig. 1, the plane of the section being indicated by the line $\alpha\alpha$, Fig. 1. Fig. 3 represents a similar section of the same, the parts being in 15 different position.

Similar letters of reference indicate corresponding parts in the several figures.

My invention relates to that class of disk steam-engines in which the disks revolve on 20 their axes in different planes; and the object of my invention is essentially to obtain a duplex engine of this character, or one capable of producing the effect of two independent engines, without comparatively increasing the 25 number of parts to the engine.

Referring to the drawings, the letter A designates a cylinder, the body of which is divided into two parts or sections, $A' A^2$, which are provided with flanges A^3 , for receiving screw-bolts whereby the sections are fastened together. Within this cylinder A are three disks, B C C, one of which, B, occupies a central position, and is inclined toward the other or outer disks, C C, which latter are parallel 35 to each other, and are mounted on the ends of independent shafts D D, the axes of which and of the outer disks coincide with each other. The central disk, B, is fitted into a guide groove or recess, E, on the inner surface of the cylinder, for the purpose of retaining said disk in 40 a fixed inclined plane, and the outer disks, C C, are fitted snugly to the inner surface of the cylinder, while intermediate thereof is a web, G, which serves the purpose of retaining the 45 outer disks a fixed distance apart from each other, and which also forms a piston to be acted on by the steam, as hereinafter described. The guide-groove E is formed at the junction of the two sections $A' A^2$ of the cylinder, where 50 the latter is enlarged in diameter for this purpose, and the web or piston G is formed on the

outer disks, C C, diametric thereto and flush with the edge or periphery of the disks at both ends. In the central disk, B, is a slot, H, for the passage of the piston G through it, the slot 55 being diametric to the central disk, and being formed by making the disk in two halves or sections, which are united by a circumferential band, J. On the opposite sides of the piston G, and axially thereto, are formed segments K K of a cylinder, which are fitted in sockets L L, formed in the opposite edges of the disk-slot H, so that by the engagement of the segments with the sockets there is formed a universal joint or bearing between the piston 60 and the central disk, the effect of which is to insure a fixed relation of these parts, at the same time permitting the piston to oscillate in the disk-slot H, as hereinafter described. The inner faces of the outer disks, C C, diverge 65 from the periphery to the center of the disks, forming cones O O, the angle of which corresponds to the angle of inclination of the central disk, B, and both of which are constantly in contact with one of the faces of the central 70 disk in a radial line, one such line of contact being diametrically opposite to the other, and the effect of the cones being to form two abutments, s s, one on each side of the central disk and concomitant to each of the steam-chambers 75 created by the spaces between the central and side disks. On opposite sides of each of the abutments s s the cylinder A is provided with two ports, Q Q, (see Figs. 1 and 2,) for the induction and ejection of steam to and from the 80 steam-chambers.

When the engine is to be used, steam is admitted to both steam-chambers through the proper port, and, acting on those portions of the piston G which are exposed in the chambers, operates to impart a revolving motion to the outer disks, C C, together with their shafts, whence such motion may be transmitted to any desired point, the central disk, B, partaking of such motion, while the piston slides laterally 90 back and forth in the disk-slot H in the ensuing change of angle or position of the piston, and inasmuch as the force of the steam is exerted at two independent points the effect of two engines is obtained, the least number of 100 parts, moreover, being used to produce such effect, due to the fact that the piston is com-

mon to both steam-chambers, while the central disk co-operates with both cones.

If desired, the cones O O may be located on the opposite faces of the central disk, B, instead of the outer disks, C C, and in that event the cones are brought in contact with the inner faces of the outer disks to form the abutments.

The device is also serviceable for pumps, water-motors, blowers, or exhaust.

Having thus described my invention, what I claim as new, and desire to secure by Letters Patent, is—

1. A duplex disk-engine having the shaft D, the disk C, having cone shaped inner faces, the central inclined disk, B, with slot H, and the diametric web G, said diametric web G and central disk, B, having a universal-joint connection, all of said parts being combined and operating substantially as described.

2. A duplex disk-engine having the two-part casing A' A², both parts having flanges A³, the said flanges forming a groove or recess, which

serves as a guide for the inclined disk of said engine, all substantially as described.

3. A duplex engine composed of a two-part casing having flanges forming a recess, a shaft suitably journaled in said casing, a central inclined disk guided in said recess and having a central slot, the walls thereof having curved faces, outer disks having cone-shaped inner faces, a diametric web passing through said central slot, segmental pieces fitted between said web and said inclined disk, and suitable inlet and outlet passages, all of said parts being combined and operated substantially as described.

4. In a duplex disk-engine, a central inclined disk having a central slot, a diametric web passing through said slot, and segmental pieces fitted between the said web and said disk, all substantially as and for the purpose set forth!

JNO. C. TELFER.
